UNITED STATES PATENT OFFICE.

EDWARD H. STEARNS, OF ERIE, PENNSYLVANIA.

IMPROVEMENT IN MACHINERY FOR HANDLING LOGS IN SAW-MILLS.

Specification forming part of Letters Patent No. 121,299, dated November 28, 1871.

To all whom it may concern:

Be it known that I, EDWARD H. STEARNS, of Erie, in the county of Erie and State of Pennsylvania, have invented certain Improved Machinery for Handling Logs in Saw-Mills, of which the following is a specification:

The invention relates to an arrangement of jack-ways for handling and delivering logs in saw-mills; and it consists in the construction and arrangement of the operating devices, whereby a log is drawn longitudinally to the mill and is then delivered laterally upon the log-carriage, as is more fully hereinafter described.

Figure I represents an end view of a frame in which are supported and shown my improvements. Fig. II is a side view of same, showing the flat-link, riveted, endless chain. Fig. III $\frac{1}{2}$ is an edge view of the sheave. Fig. III is a top view of the chain, and Fig. IV is a side view of said chain and the jack-way sloped down to the ground or water, with an idle-sheave in the lower end for the endless chain to pass over. Fig. V is a top view of the wide chain, and Fig. VI is a like view of the wide sheave to work the same.

The frame, composed of the parts A A A' and B, is fully shown in Fig. I. C is one of the head-blocks; Q, one of the knees; and B', a longitudinal section of one of the grooved track-ways; and B'' represents the side of a horizontal lateral log-roll way for delivering a log upon the carriage. In each end of this track-way are idle-sheaves d d, over which pass the endless chains J² J², which also pass over the working-sheave M' M', which may in turn be revolved by the shaft J; or the motion may be given in any other suitable manner. The grooves spoken of may be, say, a half inch in depth, of bars cast of proper form, and fastened upon the wood of the track-ways; or the track-ways may be without grooves. The use of the track-ways B'' is to furnish suitable bearings for the endless chains while they carry the log laterally from the jack-ways B' B', where logs are received from the jack-ways, or where cants are received from another sawing-machine or lumber-carrier to the carriage C, and furthermore, by means of a downward slope of the track-ways, commencing a short distance from the head-blocks, to induce the log by its own weight to roll upon them. The forms of the track-ways must be varied according to circumstances; and if, therefore, the

lateral jack-way B'' B'' should be lower than the head-block C, then the form of track-ways should be made to rise gradually upon approaching the head-block, as shown by the dotted line B², so as to elevate the chain above it, and then make a descent, down which the log will roll of itself. The jack-way should have a lateral slope toward the carriage, so that the log, when drawn up and upon it, shall of itself roll down upon the chains, and be by them carried to the downward slopes of the track-ways, and thence roll by its own weight upon the carriage, thus almost wholly avoiding manual labor in removing the log from the ground or water up and upon the saw-carriage. When it may be desired to work these chains in connection with a log-turning machine, and by the same power, one friction-wheel, K, will operate both, as in practice they are not required to operate at the same time. The friction-pulley l receives constant motion from the band-wheel M, and, having its bearings in a swinging frame, it may be thrown in contact either with pulley K to work the chains, or with friction-pulley K to operate the log-turner. The pinion L upon the shaft of the wheel K' gives motion to the idle-wheel L¹, which in turn drives the spur-wheel L², which carries the sheaves. The idle-wheel L¹ is employed to reverse the movement when driving from the same friction-wheel which operates the log-turner, and is not necessary when this machinery is not connected with a log-turner, in which case the pinion L will mesh directly with the spur-wheel L². The chains remain at rest except when the logs have to be moved laterally to the carriage, the shaft of working-sheaves M' M'' toward the frame, and by a slide slope of the horizontal part of the jack-way toward the carriage the log of itself rolls upon the chains J² J². The wide strong chain shown in Fig. V, in combination with the wide sheave shown in Fig. VI, worked together, may be used in combination with either of the track-ways, and also with the jack-way, wherever great strength is required. It will be observed that in making the large chain shown in Fig. V the two plates making one narrow link are made equal in thickness to the three composing the wider links.

I am aware that chains have been used for conveying cants and partially-sawed timber from one mill to another for resawing, and I do not

claim them in that connection, and only in the manner and for the purpose described.

I claim as my invention—

1. The combination of the track-ways B'' B'', either with or without the grooves in their top sides, and having the idle-sheaves d d, the endless chains J² J², and the working-sheaves M' M', constructed and arranged substantially as and for the purpose described.

2. The combination of the endless chain N'

(both having the same construction as J² and N') and the jack-way B', having the idle pulleys M'' and working-sheave M, with the track-ways B' B' and chains J², constructed and arranged substantially as and for the purpose described.

E. H. STEARNS.
